UNITED STATES PATENT OFFICE.

WILL ESPY CURTIS, OF EVANSTON, ILLINOIS.

PROCESS OF MAKING CELLULAR TUBES.

Application filed March 16, 1921. Serial No. 452,760.

My present invention relates in general to the art of making tubular structures and more particularly cellular structures and has special reference to the provision of an improved endless cellular tube and process of producing the same.

The particular objects of my invention are the provision of an improved tubular structure having therewithin an abutment which is fixed to the walls of the tube; the provision of a structure of the character referred to within which are arranged a plurality of spaced abutments held in predetermined spaced relationship; the provision of an improved endless tube containing an abutment; the provision of an improved circular endless tube containing a plurality of spaced abutments which are held in predetermined spaced relationship; the provision of a structure of the character referred to provided with means whereby a fluid may be introduced into the tube; the provision of an endless circular cellular tube provided with symmetrically arranged abutments and means for introducing fluid into the tube, all so arranged that the tube is closely balanced; the provision of an improved process adapted for the production of tubes of the characters referred to; together with such further and additional objects as may hereinafter appear.

In providing my improved form of tubular structure and in carrying out my improved process of producing the same, I make use of certain instrumentalities and follow certain steps which are illustrated somewhat diagrammatically in the accompanying drawing wherein—

Figure 1 is a sectional elevational view of a tube containing a number of abutments implanted therein;

Figure 2 is a transverse sectional view of the tube of Figure 1 showing one of the abutments in position therein;

Figure 3 is a sectional elevational view of a tube such as that shown in Figure 1 after it has been bent into an annular form with the abutments fixed in place therein, and

Figure 4 is an elevational view of the endless cellular structure of Figure 3, as embodied for use as a hydraulic governor member.

While tubular structures of the character referred to have various fields of employment, an important use is as part of a governor in devices for regulating the treatment

of substances chronometrically, such as are illustrated in my co-pending applications, Serial No. 150,470, filed February 23, 1917, and Serial No. 425,245, filed November 19, 1920.

Referring now more particularly to Figures 1 and 2 of the drawings, it will be observed that I have indicated, for purposes of convenience, a straight tube, 10, carrying a number of abutments, 11. The tube, 10, is conveniently cold-drawn seamless commercial tubing and the abutments, 11, may be discs of such a material, viz: iron or steel.

For use in the manufacture of hydraulic governors, it is by far preferable to employ mercury as a retarding agent, and when mercury is so employed iron or steel tubing should be utilized in view of the fact that such material is chemically inert in the presence of mercury, and does not absorb or amalgamate with or contaminate it.

Each of the abutments, 11, which is here shown as a disc-like diaphragm is provided with an aperture, 12, whereby the fluid contents of the finished endless cellular circular governor, 13 (see Figure 3) may flow from one of the cells or chambers, 14, into the next following one as the governor revolves about its axis, 15 (see Figure 4).

In producing the endless circular cellular structure of Figure 3, according to my improved process, the tube, 10, may be preliminarily heated and so caused to expand, and the relatively cool disc-like perforated diaphragms, 11, are then introduced into the tube, 10, through the open ends thereof, and are arranged therein at predetermined spaced intervals.

Inasmuch as the diaphragms are carefully made with true edges so as to have a close fit within the interior of the tube, 10, as the tube, 10, shrinks upon cooling the diaphragms will be embraced by the tube, 10, and held in intimate contact therewith.

The tube, 10, is then given a circular form as by bending it about a suitable circular mandril.

This bending will tend slightly to deform the wall of the tubular structure, 10, causing the tube to embrace and hold the abutments in position, securely fixing them to the inner surface of the tube in predetermined spaced relationship, not only frictionally but also by bending the adjacent wall portions of the tube.

The thickness of the parts, 11, prevents

them from canting or cocking within the tube as it cools or as the bending operation is carried out.

Owing to the permanent fixation of the 5 perforated diaphragms to the walls of the tube attained by the procedure described, the size of the several cells is maintained constant and invariable, notwithstanding the weight of such volume of mercury as 10 may be required for use as a governing fluid.

After the bending operation is completed 15 the ends 16 and 17 of the bent tube are brought together and suitably joined as indicated at 18.

Then for providing means for introducing the governing fluid into the tubular structure thus produced, a filling opening is made as indicated at 19, and is suitably threaded 20 for the reception of a screw, 20, which serves as removable filler plug for such opening.

Inasmuch as a slight addition is made to the weight of the structure, with respect to one side of the median line, by forming the 25 joint indicated at 18, whether such joint is formed by welding, or otherwise, the aperture, 19, and the filler plug, 20, should be disposed diametrically opposite to such joint, 18. By varying the weight of the 30 screw, 20, a very close counterweighting compensation may be made for the weight of the joint 18.

In order that the structure, 13, may be balanced in all positions, the number of the 35 abutments, 11, should be even rather than odd, and in order that the fluid which is fed on to the upper surface of any of the abutments may be quite completely discharged therefrom, the orifice of the diaphragm is 40 preferably located closely adjacent the inner perimeter of the annulus 13.

From the foregoing it will be apparent that I have provided a tubular structure 45 that may readily be made to accurate dimensions, and consequently one accurate in operation.

Having thus described my invention and illustrated its use, what I claim as new and desire to secure by Letters Patent is:—

50 1. The method of making cellular tubes which includes the steps of introducing into a tube a plurality of spaced abutments and bending the tube to hold the abutments in position.

55 2. The method of making cellular tubes which includes the steps of introducing into a tube a plurality of spaced abutments and deforming the tube to hold the abutments in position.

60 3. The method of making cellular tubes which includes the steps of introducing into a tube a plurality of spaced abutments, and

reducing the diameter of the tube adjacent to said abutments to hold them in spaced relationship.

65

4. The method of making cellular tubes which includes the steps of heating a tube, introducing into the tube a plurality of relatively spaced abutments, and shrinking said tube whereby said abutments are held in 70 predetermined spaced relationship.

5. The method of making governor tubes which includes the steps of introducing in a tube an abutment, bending the tube to embrace and hold the abutment, and joining 75 the ends of the circular tube thus produced.

6. The method of making governor tubes which includes the steps of bending the tube substantially circular and joining the ends of the tube thus produced, providing a filling aperture substantially diametrically opposite to the joint and introducing a filling member into the aperture whereby compensatory counterweight for said joint is provided.

80

7. The method of making cellular governor tubes which includes the steps of introducing within the ends of a tube a plurality of symmetrically spaced abutments, bending the tube substantially circularly 90 and thereby causing the tube to embrace said abutments and hold them in predetermined relationship, joining the ends of the cellular structure thus formed, providing a filling aperture between two of said abutments and 95 substantially diametrically opposite to the joint and introducing a filling member into the aperture whereby compensatory counterweight for said joint is provided, and a balance annulus is produced.

100

8. The method providing a bent tube with partitions therein, which comprises the steps of first positioning the partitions in a tube, and then bending the tube with the partitions therein.

105

9. As an article of manufacture, a circular structure formed of a bent tube whose ends are joined together, and which is provided with a filling opening and means for closing said opening and compensatorily counterweighting for the joint formed at said ends.

110

10. As an article of manufacture, an annulus having a series of symmetrically spaced abutments therein, and a filling opening, and means for closing said opening, the abutments being arranged in equal number on each side of a median line, and the joint of the annulus and said opening and its closing means being disposed on opposite sides of said median line.

115

In testimony whereof I have hereunto signed my name.

120

WILL ESPY CURTIS.
